UNITED STATES PATENT OFFICE.

VURLIN G. TANSEY, OF LOUISVILLE, NEBRASKA, ASSIGNOR TO HIMSELF
AND TRUMAN HALL, OF SAME PLACE.

HOLDER FOR ORNAMENTAL AND FLY PAPER.

SPECIFICATION forming part of Letters Patent No. 298,134, dated May 6, 1884.

Application filed February 19, 1884. (No model.)

To all whom it may concern:

Be it known that I, VURLIN G. TANSEY, of Louisville, in the county of Cass and State of Nebraska, have invented a new and Improved Holder for Ornamental and Fly Paper, of which the following is a full, clear, and exact description.

The object of my invention is to provide a new and improved frame for holding ornamental or fly paper on the ceiling of a room, either at the middle or in the corners, in such a manner that the ceiling of the room need not be defaced.

The invention consists in a frame for holding fly or ornamental paper, which frame is constructed with a series of spring-frames on which the paper can be attached, and with a series of cords extending from the outer rod of the frame to the inner plate, from which cords the paper is suspended.

The invention also consists in various parts and details and combinations of the same, as will be fully described and set forth hereinafter.

Reference is to be had to the accompanying drawings, forming part of this specification, in which similar letters of reference indicate corresponding parts in all the figures.

Figure 1 is a plan view of my improved ornamental paper - holder, showing it partly folded and partly unfolded. Fig. 2 is a longitudinal sectional elevation of the same, showing it unfolded. Fig. 3 is an enlarged plan view of the middle part of the paper-holder. Fig. 4 is a plan view of one of the sections to be located in the corner.

The holder is formed of four quadrant-sections, and each section is formed of a quadrant-wire, A, held by two or more radial arms, B, on a quadrant-plate, C, having its edge bent down and a flange, D, formed at the said edge. The arms or rods B are provided near their outer ends with laterally-projecting arms E, and on the said arms E V-shaped or other frames F are hung, which can be folded down inward to rest on the plates C, or can be folded outward to project beyond the outer wire or rod, A. To the upper surface of the flange D a series of hooks, G, or headed studs G' are secured, and a series of cords, H, arranged

radially are secured to the hooks G or the studs G', and to the outer wire or rod, A. The said cords can be spaced a greater or less distance from each other, as may be desired. The inner corner of each plate C is clipped off, as shown at J in Fig. 3, so that the said plates can be placed around a chandelier tube or hook in the middle of the ceiling for the purpose of supporting the frame. If a circular paper-holder is formed, four quadrant sections are united, the plates C being united either by means of a hook, K, held on one section and passed into a staple on the next section, by clips L, screwed on two adjoining plates, C, by a U-shaped wire or locking-pin, M, passed through sleeves N on the edges of two adjoining sections, or the sections can be united by a plate held on the under side, and screws passed through the plate into the sections, or in any other suitable manner.

The ends of the wires A need not be united. If the paper is to be held in a corner, a single quadrant-section is used, as shown in Fig. 4; and if the paper-holder is to be held to the ceiling of the room at the side, two quadrant-sections are united to form a semicircular paper-holder. The ornamental paper is suspended from the cords H, extending from the plates C to the outer wire or rod, A, and is secured to the sides of the frames F, as shown in Fig. 2. The paper can be of any desired pattern, size, or color, or can be arranged in any suitable manner. Poison fly-paper or adhesive fly-paper can also be secured to the frame.

While transporting the frame, or when the same is stored away, the frames F are folded down upon the upper surface of the frame, so as to occupy as little space as possible.

The advantages of my improved paper-holder are that no tacks or nails need be driven into the ceiling, which thus is not defaced; that the paper can be hung on the frame, which is held in such a position that it will be convenient for the person hanging the paper, thus enabling a person to hang a greater quantity of paper in a given time than he could hang if he had to hang it on cords secured to nails in the ceiling; and that the paper can be readily exchanged, and the papers can be arranged

much more handsomely than they could in the usual way.

Having thus described my invention, what I claim as new, and desire to secure by Letters 5 Patent, is—

1. A frame for holding ornamental paper, consisting of a wire frame adapted to be held on the ceiling, and adapted to hold ornamental or fly paper, substantially as herein shown and 10 described.

2. The combination, with a frame for holding ornamental and fly paper, of swinging frames adapted to be projected over the edges of the frame to which they are hinged, which 15 swinging frames are also adapted to hold fly paper or ornamental paper, substantially as herein shown and described.

3. In a frame for holding ornamental and fly paper, the combination, with a curved wire 20 or rod, A, of a plate, C, the rods B, uniting the wire or rod A and the plate C, and of swinging frames F, pivoted on laterally-projecting arms E of the rods B, substantially as herein shown and described.

25 4. In a frame for holding ornamental and fly paper, the combination, with a curved rod or wire, A, of the plate C, connected with the wire A by the rods B, and the cords H, extending from the edge of the plate C to the wire A, 30 substantially as herein shown and described.

5. In a frame for holding ornamental and fly paper, the combination, with the curved rod or wire A, of the plate C, connected with the rod or wire A by the rods B, hooks, or other projections G, on the flange of the plate C, 35 and the cords H, extending from the said hooks or projections to the curved wire or rod A, substantially as herein shown and described.

6. A frame for holding ornamental and fly paper, consisting of four quadrant-sections, 40 each formed of a quadrant-wire held by arms on a quadrant-plate, the quadrant-plates being united with each other by means of clips, hooks, or other suitable devices, substantially as herein shown and described.

45 7. In a frame for holding ornamental and fly paper, the combination, with the four quadrant plates united with each other, of four quadrant wires or rods connected by radial arms with the quadrant-plates, and of swinging frames held on the radial arms and adapted to be projected beyond the quadrant-wires, 50 substantially as herein shown and described.

VURLIN G. TANSEY.
